UNITED STATES PATENT OFFICE

FRANCIS PETELER, OF CINCINNATI, OHIO, ASSIGNOR TO EDWIN PETELER,
OF BLOOMINGTON, MINNESOTA.

IMPROVEMENT IN STATION-INDICATORS.

Specification forming part of Letters Patent No. 174,291, dated February 29, 1876; application filed December 9, 1875.

To all whom it may concern:

Be it known that I, FRANCIS PETELER, of Cincinnati, Hamilton county, Ohio, have invented a new and useful Station-Indicator, of which the following is a specification:

My invention relates to a device adapted to be posted in a conspicuous position in a railway-car or other public vehicle, said device being so constructed as to convey information of the name of the next station by the display of a placard in a suitable frame or case.

In the most complete form of my invention provision is made for striking a bell or other resonant body in the act of shifting the sheet or band to bring the placard of the next station into view.

In the accompanying drawing, Figure 1 is a front elevation of my indicator. Fig. 2 is an elevation of the same after the front has been removed. Figs. 3, 4, and 5 are transverse sections at the lines 1 1, 2 2, and 3 3, respectively. Fig. 6 is a horizontal section at the line 4 4. Fig. 7 is a perspective view of one of the dovetails. Fig. 8 is a horizontal section through another form of dovetail, and of its socket. Fig. 9 is an enlarged transverse section of one of the sheet-rollers.

A represents a box or case. B is a window in the front of said case, for the purpose of allowing the names of the stations to be seen as they are successively brought to view. Secured to the back of this box are tapering hooks, tongues, or dovetails a a', which engage in appropriate sockets C C', that are attached to each inner end of the car. By this arrangement the box is capable of being readily detached from one end of the car and applied to the other end, it being understood that the indicator is at all times to face and be in full view of the passengers. Journalized longitudinally of the box and within the same are two drums, D D', upon which are mounted clamps d d', that enable the attachment of the ends of the sheet, band, or strip F, that is wound from one drum to the other. This band has inscribed upon it the names of the successive stations to be indicated. The shaft of each drum terminates outside the box in an arbor, e, for the application of a key, E, by which the conductor is enabled to wind the

band onto either drum, so as to expose the next station to view. At the same time studs H, upon one or both of the drum-heads, operate, through a suitable bell-crank, g, and hammer g', to strike a bell, G, or other resonant body. Rollers I I' serve to hold the band to its proper vertical and flat position behind the window B. A rod, M, having a handle, m, outside of the box, and a finger, N, at its inner extremity, enables the operator to temporarily suspend the operation of the striking mechanism, so as to avoid useless sounding of the bell while shifting or setting the band for commencement of the daily signals, or for avoidance of false signals in passing stations not stopped at. A torsion-spring, O, serves to automatically retract the finger N, so as to leave the alarm at liberty the moment it is released from the operator's grasp. Springs or brakes P, which press upon the necks p of the winding-drums, serve to hold them against any accidental unwinding without interfering with their rotation by the operator, as above stated. The dovetails for engagement with the car may, if preferred, project from the ends instead of the back of the case.

The operation of my indicator is as follows: As soon as the train leaves a station the attendant turns one of the drums D or D' far enough to cause such a movement of the band F as will suffice to bring the name of the next station to view. As the drums rotate, the hammer g' is caused to strike the bell G, and to thereby give audible notice to the passengers that a station is being approached.

The above-described operations of shifting the band and ringing the bell are repeated every time the cars leave a station, so that when the train has reached the end of the route said band will be completely uncoiled from one drum and wound upon the other one. The attendant then shifts the indicator to the other end of the car, and on the return trip he uncoils the band gradually from station in the opposite direction, the bell announcing every change of the indicator to the passengers.

It will thus be seen that one indicator suffices for each car in both directions, and therefore is much simpler and less liable to derange.

ment than if two bands were employed. The audible signal can be operated from any moving member of the apparatus. The shafts of the winding-drums may be operated by appliances external to the car, and not by attendants of the train.

I claim as new and of my invention—

1. The combination of paired drums D D' rollers I I', inscribed band F, arbors e, springs or brakes P, and audible signal apparatus H G g', with open-faced box or case A B.

2. The combination with said audible-signal apparatus of the finger N, having the handle M m, and self-retracting spring O, for the purpose designated.

In testimony of which invention I hereunto set my hand.

FRANCIS PETELER.
